UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,852**, dated September 2, 1873; application filed August 9, 1873.
[Term of Patent 3½ years.]

I.

To all whom it may concern:

Be it known that I, FREDERICK WINK, of Philadelphia, Pennsylvania, have invented a Design for a Shawl-Pattern, of which the following is a specification:

My design for shawl-pattern is fully represented by the figure in the accompanying drawing, the remainder being merely a repetition of that which appears.

The members of the stripe A, which constitutes the main feature of the pattern, consist of minor parallel stripes, bars, or ribs of different widths and shades or colors, some being plain and others elaborately ornamented. The ornamented member a is composed of a series of parallel ribs of slightly different

shades, upon which are short rows of dots staggered, as shown. The ornamented member b is composed of short transverse and zig-zag ribs, arranged in a manner too clearly shown to need description.

Irrespective of the colors employed, I claim—

The design for a shawl-pattern, as described, and as represented in and by the accompanying drawing.

In testimony whereof I have signed my name to this specification in the presence of two subscribing witnesses.

FRED. WINK.

Witnesses:

CLINTON M. LATOURETTE,
LEWIS T. GODFREY.
